UNITED STATES PATENT OFFICE.

WILLIAM R. BAKER, OF CHICAGO, ILLINOIS, ASSIGNOR TO THE McCORMICK HARVESTING MACHINE COMPANY, OF SAME PLACE.

MOWER.

SPECIFICATION forming part of Letters Patent No. 398,307, dated February 19, 1889.

Application filed March 12, 1885. Serial No. 158,621. (No model.)

To all whom it may concern.

Be it known that I, WILLIAM R. BAKER, a citizen of the United States, residing at Chicago, in the county of Cook and State of Illinois, have invented certain new and useful Improvements in Mowers, of which the following is a specification.

My invention relates particularly to that class of mowers known as center-draft—that is, in which the finger-bar and cutter fill the space in front of the two wheels, and the tongue extends forward centrally over said finger-bar to bring the team in front thereof; and it consists in a continuous main frame extending from the end of the finger-bar at one side back behind the axle, to which it is bolted, then bent and carried to the other side of the machine, where it is a second time bent and carried to the axle on that side and bolted thereto; in combining with such main frame a diagonal brace bolted to the flaring longer arm thereof and to the rear transverse bar, and in the various other combinations and details of construction hereinafter pointed out and claimed.

In the drawings, Figure 1 is a top plan view of a center-draft mower embodying my invention. Fig. 1^a is a detail of the frame. Fig. 2 is a side elevation thereof; Fig. 3, an enlarged detail in plan of the mechanism at the heel end of the cutter-bar. Fig. 4 is a side elevation thereof; Figs. 5 and 6, respectively, enlarged details in plan and side elevation (from the inner side) of the construction at the opposite end of the finger-bar; and Fig. 7, an enlarged detail of the pitman which connects the cutter and the bell-crank.

A is the axle, herein shown as a cylindrical metal shaft, to afford a pivot for the draft-frame, and B represents the carrying-wheels turning loosely on said axle. Sleeved upon the axle are a couple of bracket-castings, b, connected by a metal bar, b', which extends from one to the other, parallel with and immediately in front of said axle, and from these castings hounds b² reach diagonally forward until they meet the draft-tongue C, which at its rear supports a spring-standard for the seat C', and is yoked to the axle by a curved or clip bolt, which may also serve to secure

the seat-standard, as shown. The space between the hounds is filled with planking to form a platform.

Thus far the construction is substantially the same as already known in machines of this class.

The main frame consists, primarily, of a single bar, D, of pipe-iron, having one long arm, d, and one short arm, d', both arms being parallel with the inner faces of the wheels on their respective sides of the machine, and the uniting portion being behind and parallel with the axle, but practically just outside the tread of the wheel at the rear, depending somewhat on the diameter of the main gear. The short arm terminates with and is bolted to the axle on its side, between the adjacent wheel and the bracket-bearing for the draft-frame just described. The longer arm is also bolted to the axle on its own side of the machine, in similar relation to the wheel and bracket-bearing at that point, but extends forward, still parallel with the face of the wheel, until it reaches the front tread, when it flares outwardly a short distance to bring the end of the finger-bar, which it supports, in front of the tread, that a clean cut may be made in the path of the wheel. Behind the axle this frame is further strengthened by a tubular or pipe-iron tie-bar, E, parallel with the rear bar of the frame and united to the side arms by "T's" or T-couplings e e', as shown, which are respectively right and left threaded, so that by means of corresponding male threads upon the interlocking ends of the tie-bar the latter may be driven home by means of a wrench and the frame tightened until its arms are in their proper position. From the flaring end of the longer arm of the frame a brace, E', is carried diagonally back beneath the axle to this tie-bar E, to which it is bolted, and thence is carried on to the rear bar of the frame D and again bolted. It may also be bolted or clipped to the axle. This construction affords a very strong, rigid, and yet extremely light frame. To the front end of the longer frame-bar, d, is secured a casting, F, which has bearings f for the journals of a bell-crank, F', and has also beneath and slightly in advance of said bearings a

- ball, f' , to form one member of a universal coupling with the heel of the shoe on the finger-bar at that end. Beyond this it is cut away beneath, but bridges the shoe to near its forward end, where it has a subtending flange, f'' , upon which the toe of the shoe rests with liberty to play up and down. At the extreme front the casting is slotted vertically, or nearly vertically, for the reception of the shank of a stud-axle, upon which one of the lead-wheels F^2 turns, and by means of a clamping-nut said wheel can be adjusted up and down to change the normal height of cut. The shoe g at this end of the finger-bar G has in its heel a socket, g' , to receive the aforementioned ball from the casting, and a cap-piece, g'' , correspondingly cupped, which is bolted over and confines said ball, thus completing the universal joint.
- Near the heel of the cutter-bar H is a ball-stud, h , and the adjacent end of the bell-crank, as also its farther end, has also a ball-stud. The connection between the bell-crank and the stud and the cutter-bar is made by a short link, I , which, on account of the ball-joints, will not interfere with the tilting or rocking or other flexions of the finger-bar upon the universal coupling. This link or pitman I have, for the purpose of taking up wear, constructed in the following manner: It is composed, primarily, of a substantially rectangular frame, i , widened at certain points and at others narrowed, as shown, being narrowed, however, at both ends. At the farther end it is rounded and thickened to form a seat, i' , that has a hemispherical socket to receive one side of the ball-stud from the heel of the cutter-bar. After this comes a block, i^2 , having grooved sides to embrace the bars of the frame, but cupped at both ends and narrower in the middle than at the ends, so as to be slipped into the frame by matching with certain of its spacings that embrace the other side of the stud, while receiving in its opposite cup the stud from the bell-crank, and a short block or follower, i^3 , cupped on its inner side, comes last of all, guided, like the others, by engagement with the bars at the narrower part of the link-frame. Finally, a set-screw, i^4 , threaded into an enlargement at the outer end of the frame, presses upon the follower, and may at any time be adjusted to bring the parts closer together, and thus take up wear.
- The opposite, or what may be termed the "free," end of the finger-bar, since it is to be permitted to rise and fall irrespective of the movement of the main frame, is kept in alignment by means of a link or thrust-bar, K , pivoted to the main frame or to the axle, and also to the casting supporting the finger-bar on that side of the machine. In the present instance I have shown this thrust-bar as connected at its rear end to the T , which unites the main-frame bar and the tie-bar at that side of the machine by a ball-and-socket joint,

k , the socket being formed in a web filling one angle of said T . The necessity for a universal joint at this end of the thrust-bar is occasioned by the universal coupling between what I will call the "heel" end of the finger-bar, or that end connected with the longer arm of the main frame and the casting at that point, and the consequent resultants of the flexions, independent of the movement of the main frame, intended to be permitted to the free end of the finger-bar by means of the thrust-bar, and the joint is placed at the intersection of the main bar and its tie-bar merely for convenience, although it should be at least as far back as the axle for good effect.

At the front end the thrust-bar is connected by an upwardly-trending or practically vertical pivot-pin, k' , with the forward end of a casting, L , which has an upright slot in front for the adjustable reception of the shank of a stub-axle supporting the lead-wheel at this end, and, like the other casting, bridges the shoe, and has a subtending flange, l , at its forward end, upon which the point of said shoe is supported, but is connected to the heel of said shoe by a horizontal pivot-pin, l' , instead of a ball-joint, for which there is no necessity at this end.

For the purpose of raising the cutter-bar a rock-shaft, M , is mounted in bearings m , afforded by the sleeved brackets which support the draft-frame, and has at its end two segments, m' , one over the long arm of the pipe-frame or main frame and one over the link or thrust-bar at the opposite side of the machine. From these segments chains are carried, respectively, to the arm and link. An ordinary lever, with its rack and locking-dog, is attached to the rock-shaft in a convenient position to be reached by the driver, so that by rocking the shaft in one direction the chains may be wound upon the segments and the finger-bar lifted, and by rocking it in the other direction the chains will be let out. The purpose of this is to avoid unusual obstructions, as the lead-wheels will be sufficient to keep the finger-bar clear under all ordinary circumstances, and also to lift and carry the finger-bar when turning in the field and for transportation.

In bearings near the rear of the frame is mounted the driving-shaft N , having ratchet-clutched pinions n at its ends, engaging with annular gears O on the carrying-wheels, and bearing a spur-gear, P , which turns loosely on the shaft, and is engaged therewith at will by means of a clutch, p , controlled by the driver. This meshes with and drives a small pinion, Q , fast to a short counter-shaft, q , supported in a bracket-casting depending from the main frame, and this counter-shaft bears at its outer end, between the carrying-wheel and the long frame-bar, the wrist-pin for the pitman S , whereby motion is communicated to the bell-crank and ultimately to the cutter.

The operation of the machine will be plain from the foregoing description and needs no further statement.

I claim as my invention—

5 1. The combination, substantially as hereinbefore set forth, in a center-draft mower, of a main frame having one long arm connected to the rear of the finger-bar at its heel end by a universal joint, and a link or thrust-bar 10 connected to the rear of the finger-bar at the other end by a hinge-joint, and to the main frame by a universal joint.

2. The combination, substantially as hereinbefore set forth, in a center-draft mower, of 15 a main frame having one long arm connected to the rear of the finger-bar at its heel end by a universal joint, and a link or thrust-bar having an upwardly-trending pivotal connection with the finger-bar at its forward end.

20 3. The combination, substantially as hereinbefore set forth, in a center-draft mower, of a main frame having one long arm connected to the rear of the finger-bar at its heel end by a universal joint, and a link or thrust-bar 25 having an upwardly-trending pivotal connection with the finger-bar at its forward end, and universally jointed to the main frame at its rear end.

4. The combination, substantially as hereinbefore set forth, in a center-draft mower, of 30 a main frame having one long arm connected with the rear of the finger-bar at its heel end by a universal joint, and a casting in which the other end of the finger-bar is carried, a hinge-joint between said casting and the rear of the finger-bar at that end, and a link or thrust-bar connected with said casting by a practically-upright pivot.

5. The combination, substantially as hereinbefore set forth, in a center-draft mower, of 40 a main frame having one long arm connected with the rear of the finger-bar at its heel end by a universal joint, a casting in which the other end of the finger-bar is carried, a hinge-joint between said casting and the rear of the finger-bar at that end, and a link or thrust-bar connected with said casting by a practically-upright pivot and with the main frame 45 by a universal joint.

50 6. The combination, substantially as hereinbefore set forth, in a center-draft mower, of a main frame having one long arm connected with the rear of the finger-bar at its heel end by a universal joint, a bell-crank in bearings 55 rigid with said arm adjacent to the finger-bar, and a short pitman connecting a ball-stud in one end of said bell-crank with a ball-stud on the heel of the cutter-bar, and a link or thrust-bar connected to the rear of the finger-bar at the other end by a hinge-joint and to the main frame by a universal joint, whereby the finger-bar is permitted to tilt or rock to follow the sinuosities of the ground and to rise and fall at the link-connected end irrespective of the motion of the main frame and without interfering with the driving of the cutter.

7. The combination, substantially as hereinbefore set forth, in a center-draft mower, of the main frame, thrust-bar, the castings connected, respectively, to the long arm of the main frame and to the thrust-bar, the finger-bar hinged at its rear to said castings, the subtending flanges or ledges on said castings upon which the toes of the shoes rest, and the 70 lead-wheels secured to said castings in advance of the finger-bar.

8. The combination, substantially as hereinbefore set forth, in a center-draft mower, of the main frame, the thrust-bar, the castings connected, respectively, to the long arm of the main frame by a rigid joint and to the thrust-bar by a practically-upright pivot, and the finger-bar united at its rear with the first casting by a universal joint and with the second 85 by a hinge-joint.

9. The combination, substantially as hereinbefore set forth, in a center-draft mower, of the main frame, the thrust-bar, the castings connected, respectively, to the long arm 90 of the main frame by a rigid joint and to the thrust-bar by a practically-upright pivot, the finger-bar united at its rear with the first casting by a universal joint and with the second by a hinge-joint, and the subtending ledges 95 or flanges from said castings upon which the toes of the shoes rest.

10. The combination, substantially as hereinbefore set forth, with the long arm of the main frame, of a casting having ears for the 100 reception of the bell-crank and a forward-projecting ball to form a universal joint with the heel of the shoe, a subtending flange or ledge in front to support the toe of said shoe, and provision for the attachment of a lead-wheel in advance of said shoe.

11. In a center-draft mower, the main frame formed of a single bar extending from the axle at one side toward the rear parallel with the wheel, then bent at right angles to itself 110 and carried to the other side, and again bent and passing alongside the wheel on that side to its forward tread, and there flaring outwardly to its point of connection with the finger-bar, combined with a through-axle, to 115 which both arms of the frame are bolted.

12. In a center-draft mower, the main frame, consisting of a single bar of pipe metal bolted to the axle at one side adjacent to the wheel and extending rearwardly parallel with said wheel to near its tread, then bent at right angles to itself and carried to the other side adjacent to the wheel on that side, and again bent and carried parallel with the inner side of that wheel past the axle, to which it is 120 bolted, to near the front tread of the wheel, and finally flaring outwardly to its point of connection with the finger-bar.

13. The combination, substantially as hereinbefore set forth, in a center-draft mower, of the main-frame bar, of a single length of pipe metal bent into the form described, the tie-bar, also of pipe metal and having its ends 130 respectively right and left screw threaded,

and the **T**-couplings which unite the frame-bar and the tie-bar.

14. The combination, substantially as hereinbefore set forth, in a center-draft mower, of the main-frame bar bent into the form described and a diagonal brace bolted to its flaring longer arm and to the rear arm.

15. The combination, substantially as hereinbefore set forth, in a center-draft mower, of the tubular main-frame bar bent into the form described, the tubular tie-bar and **T**-couplings, and the diagonal brace.

16. The casting F, having bearings *f* for the journal of the bell-crank, and slotted at its forward end to adjustably receive the shank of a stub-axle for the lead-wheel.

17. The casting F, having near its rear an outwardly-projecting ball-stud and at its front a subtending ledge or flange and cut away therebetween to form a bridge.

18. The casting F, formed, substantially as described, with bearings *f*, a ball-stud, *f'*, and subtending flange *f*², and an upright slot for the reception adjustably of the shank of a stub-axle for the lead-wheel.

19. The **T**-coupling *e'*, formed with a web in one of its angles having a ball-socket for the rear end of the thrust-bar.

WILLIAM R. BAKER.
